Attorney

UNITED STATES PATENT OFFICE.

THOMAS E. METTLIN, OF AMES, IOWA, ASSIGNOR OF ONE-TENTH TO JAMES H. GIL-CHRIST, ONE-TENTH TO C. J. MORGAN, SEVEN-TENTHS TO CLYDE L. SIVERLY, AND ONE-TENTH TO ROGER H. WILLIAMS, ALL OF AMES, IOWA.

LIQUID-HYDROCARBON BURNER.

1,289,222.

Specification of Letters Patent. Patented Dec. 31, 1918.

Application filed April 15, 1918. Serial No. 228,674.

To all whom it may concern:

Be it known that I, THOMAS E. METTLIN, a citizen of the United States, residing at Ames, in the county of Story and State of 5 Iowa, have invented certain new and useful Improvements in Liquid-Hydrocarbon Burners, of which the following is a specification, reference being had to the accompanying drawings.

10 This invention relates to certain improvements in liquid hydro-carbon burners and has relation more particularly to a device of this general character especially designed and adapted for use in connection with a 15 plumber's melting pot and it is an object of the invention to provide a novel and improved burner of this kind which permits the use of low gravity oil as a fuel and which burner operates without smoke irrespective of the grade or gravity of the oil. 20

Another object of the invention is to provide a novel and improved burner of this type which produces greater heat with less fuel when considered in connection with 25 burners of a similar type now generally employed.

Another object of the invention is to provide a novel and improved burner of this general character which includes a metallic 30 member having a socket or pocket therein with the inner end thereof enlarged to afford a mixing chamber and wherein openings are in communication with the mixing chamber substantially tangential to the circumference 35 thereof whereby a rotary movement is imparted to the fuel or vapor resulting in a thorough mixture of the air and vapor.

A still further object of the invention is to provide a novel and improved device of 40 this general character including a metallic block having a socket or pocket therein with the lower portion enlarged to afford a mixing chamber together with air vents in communication with the mixing chamber and 45 wherein said block has disposed therethrough a series of connected ducts discharging within the mixing chamber and adapted for communication with a source of fuel supply, said ducts affording an effective

means for vaporizing the fuel before entering within the mixing chamber. 50

The invention consists in the details of construction and in the combination and arrangement of the several parts of my improved liquid hydro-carbon burner whereby 55 certain important advantages are attained and the device rendered simpler, less expensive and otherwise more convenient and advantageous for use, as will be hereinafter more fully set forth. 60

The novel features of my invention will hereinafter be definitely claimed.

In order that my invention may be the better understood, I will now proceed to describe the same with reference to the accompanying drawings, wherein:

Fig. 1 is a view in perspective of a burner constructed in accordance with an embodiment of my invention;

Fig. 2 is a vertical sectional view taken 70 diagonally of the burner as disclosed in Fig. 1;

Fig. 3 is a sectional view taken substantially on the line 3—3 of Fig. 2; and

Fig. 4 is a sectional view taken substantially on the line 4—4 of Fig. 2. 75

My improved burner as herein disclosed comprises a metallic body or block B and one face of the block is provided with the socket or pocket 1 and the outer or open end 80 of said pocket or socket 1 serves as an exit for the flame created by igniting the vapor within the pocket or socket 1, or particularly the outer end portion thereof.

The inner end portion of the pocket or 85 socket 1 is enlarged transversely to afford a mixing chamber M preferably cylindrical in form and produced in the block or body B and in communication with the mixing chamber M are the openings or ports 2 affording means whereby air may be admitted within the chamber M to mix with the vaporized hydro-carbon fuel delivered within said chamber M. The openings or ports 2 are substantially tangential to the peripheral wall of the chamber M so that the air entering into the chamber M through said openings 2 produces a rotary motion within 95

said chamber and thereby more thoroughly mixes with the fuel vapor before the ignition of the vapor within the outer end portion of the socket or pocket 1 and which 5 outer end portion constitutes a combustion chamber C. This action of the vapor within the chamber M as created by the entrance of air through the openings 2 also serves to effect the desired discharge of the flame at 10 the exit.

As is particularly illustrated in Fig. 2 of the drawings it is to be noted that the lower portion of the combustion chamber C is gradually enlarged as indicated at a so that 15 no hindrance or interference will be offered to the mixture passing from the chamber M into the chamber C.

The upper portion of the body or block B at opposite sides of the socket or pocket 1 20 is provided with the ducts 3 and 4 opening at corresponding ends through one face of the body or block B and the inner ends of the ducts 3 and 4 are in communication through the medium of the intermediate 25 connecting duct 5. The duct 5 has one end opening through a second face of the block or body B. In communication with the open end of the duct 3 is the conduit or pipe 6 which leads from a suitable source of fuel 30 supply. The open ends of the ducts 4 and 5 are normally closed by the removable plugs 7. It will be self-evident that upon removing the plugs 7 and the conduit or pipe 6, the ducts 3, 4 and 5 may be cleansed when 35 the occasions of practice may require.

In communication with the duct 4 adjacent its open end is the duct 8 extending through the body or block B in a direction substantially parallel to the longitudinal 40 axis of the socket or pocket 1. The top or outer end of the duct 8 is open and is normally closed by the removable plug 7. The lower end of the duct 8 is in communication with the duct 9 extending inwardly of the 45 block at a point below the pocket or socket 1 and the outer end of the duct 9 is open but normally closed by the removable plug 7.

Disposed through the lower face of the body or block B at substantially the axial 50 center of the chamber M and in communication with said chamber is a needle valve N and the inner end portion of the duct 9 is in communication with the exit end of the needle valve N. The valve element or stem 10 55 comprised in the needle valve N may be adjusted into open or closed position in any manner desired. The liquid fuel as it passes through the ducts 3, 5, 4, 8 and 9 is vaporized when delivered within the chamber M 60 through the needle valve N and which vaporization is effected by the heat generated within the combustion chamber C and contained within the body or block B. It has been fully demonstrated in actual practice

that my improved burner as herein described 65 and illustrated can be employed with an oil of low gravity to generate a flame free of smoke and which can be burned without danger or attention.

From the foregoing description, it is 70 thought to be obvious that a liquid hydro-carbon burner constructed in accordance with my invention is particularly well adapted for use by reason of the convenience and facility with which it may be assembled 75 and operated and it will also be obvious that my invention is susceptible of some change and modification without departing from the principles and spirit thereof and for this reason I do not wish to be understood as 80 limiting myself to the precise arrangement and formation of the several parts herein shown in carrying out my invention in practice except as hereinafter claimed.

I claim:

1. A burner of the class described consisting of a block of heat conducting material provided with a pocket open at a face of the block and closed at its inner end, said block having communicating ducts therein leading 90 from a face of the block to the inner end portion of the pocket, and air openings disposed through the block and in communication with the inner end portion of the pocket.

2. A burner of the class described consisting of a block of heat conducting material provided with a pocket open at a face of the block, said block having communicating ducts therein leading from a face of the block to the inner end portion of the pocket, 100 and air openings disposed through the block and in communication with the inner end portion of the pocket, said air openings being substantially tangential to the pocket.

3. A burner of the class described consisting of a block of heat conducting material provided with a pocket open at a face of the block and closed at its inner end, said block having communicating ducts therein leading 105 from a face of the block to the inner end portion of the pocket, and air openings disposed through the block and in communication with the inner end portion of the pocket, the inner end portion of the pocket being enlarged.

4. A burner of the class described consisting of a block of heat conducting material provided with a pocket open at a face of the block and closed at its inner end, said block having a duct leading from a face of the 120 block adjacent the open end of the pocket and partially surrounding said open end portion of the pocket, said duct being continued longitudinally of the pocket and communicating therewith at the closed end 125 thereof, said block being provided with air openings in communication with the pocket adjacent its closed end.

5. A burner of the class described consisting of a block of heat conducting material provided with a pocket open at a face of the block and closed at its inner end, said block having communicating ducts therein leading from a face of the block to the inner end portion of the pocket, and air openings disposed through the block and in communica-

tion with the inner end portion of the pocket, and means coacting with the duct in communication with the inner end portion of the pocket for controlling the flow through said duct into the pocket. 10

In testimony whereof I hereunto affix my signature.

THOMAS E. METTLIN.
